UNITED STATES PATENT OFFICE.

JOHN H. STONE, OF CRANSTON, RHODE ISLAND.

DESIGN FOR A CLASP.

60,068.

Specification for Design.

Patented Dec. 20, 1921.

Application filed May 7, 1919. Serial No. 295,501. Term of patent 14 years.

To all whom it may concern:

Be it known that I, JOHN H. STONE, a citizen of the United States, residing at Edgewood, city of Cranston, county of Providence, State of Rhode Island, have invented a new, original, and ornamental Design for a Clasp, of which the following is a specification, reference being had to the accompanying drawing, forming part thereof.

Figure 1 is a perspective view showing a clasp in open position, illustrating my new design.

Fig. 2 is a view of the under side of the clasp showing the shape or configuration thereof in closed position, illustrating my new design.

Fig. 3 is a section on line 3—3 of Fig. 2, illustrating the hollow rim formed in one of the arms of a clasp, illustrating my new design.

I claim:

The ornamental design for a clasp, as shown.

JOHN H. STONE.
